UNITED STATES PATENT OFFICE.

MICHAEL BECK, OF MINNEAPOLIS, MINNESOTA.

INTERNAL-COMBUSTION ENGINE.

Application filed January 8, 1921. Serial No. 435,975.

To all whom it may concern:

Be it known that I, MICHAEL BECK, a citizen of the United States, residing at Minneapolis, in the county of Hennepin and State of Minnesota, have invented certain new and useful Improvements in Internal-Combustion Engines; and I do hereby declare the following to be a full, clear, and exact description of the invention, such as will enable others skilled in the art to which it appertains to make and use the same.

My present invention has for its object to provide an internal combustion engine of greatly increased efficiency, capable of being made in any desirable number of units and having certain advantages over the standard type of engine, all as will be hereinafter described and defined in the claims. As a primary feature of the invention, the cylinders and pistons are incorporated in structures that constitute also a connection between a master crank and a pivotal support, to which pivotal support a rotary valve, controlling admission and exhaust, is mounted. In the preferred arrangement, the cylinders are journaled on and move in proper order with the cranks to which they are connected and the non-reciprocating pistons oscillate on or around the rotary valve and are provided with spring-pressed receiving heads, which perform important functions to be hereinafter described. The invention also involves other important novel features to be hereinafter noted.

In the drawings, which illustrate a four-cylinder or four-unit engine, each of which is of the four-cycle type, like characters indicate like parts throughout the several views.

Referring to the drawings:

Fig. 1 is a vertical section showing all of the cylinders in axial section;

Fig. 2 is a transverse section of the engine, the master crank being turned ninety degrees from the position shown in Fig. 1;

Fig. 3 is an enlarged section on the line 3—3 of Fig. 2, some parts being broken away;

Fig. 4 is a horizontal section on the line 4—4 of Fig. 3;

Fig. 5 is a horizontal section on the line 5—5 of Fig. 3; and

Figs. 6, 7, 8 and 9 are enlarged sections taken respectively on the lines 6—6, 7—7, 8—8 and 9—9 of Fig. 1.

The various running parts of the engine are preferably mounted in an inverted V-shaped main housing 10, to the bottom of which is secured a crank chamber 11 adapted to contain water y and, on top of the water, lubricating oil y^1 . Air-circulating pipes 12, for keeping the oil and water cool, are shown as extended through the crank chamber 11.

Journaled in suitable bearings 13, at the junction of the housing 10 and crank chamber 11, is a master crank shaft 14, which, for the four cylinders employed, has four cranks. The numeral 15 indicates a fly wheel or combined pulley and fly wheel secured to one outer end of the engine crank shaft.

At its apex or top, the housing 10 is formed with a cylindrical valve casing 16 in which is journaled a rotary valve consisting, as shown, of an outer cylindrical sleeve 17, an inner cylindrical sleeve 18 and connecting heads 19. This rotary valve controls both admission and exhaust and is formed with an inner chamber 20 and an annular outer chamber 21. The chamber 20 is used for admission and the chamber 21 for exhaust, but this arrangement might be reversed. The arrangement of ports in said rotary valve will be later noted.

Each engine unit comprises a cylinder 22, the closed outer end of which is journaled on the co-operating crank of the master crank shaft. These cylinders 22, around their main body portions, have spiral conduits 23, which, at their lower ends, lead from intake ports 24 formed in depending portions of the cylinder heads and preferably provided with check valves 25, see Fig. 2. At its upper extremity, the conduit 23 terminates in ports 26, (see particularly Figs. 1 and 3).

Working within each cylinder 22 is a cylindrical piston 27, the upper end of which is rigidly secured to a tubular connecting rod 28. The several tubular connecting rods 28, at their upper ends, are provided with transversely extended sleeve-like heads 29 pivoted for oscillatory movements on the outer cylinder 17 of the rotary controller valve and within the fixed valve casing 16, the latter being cut away at its under side at 16^a to afford clearance and permit movements of said piston rod.

Working within the cylindrical piston 27 is a receding piston head 30, which, as

shown, has an axial sleeve 31. The numeral 32 indicates a so-called port-extending tube that is telescoped through the receding head 30 and its sleeve 31, is extended axially 5 through the tubular connecting rod 28, and at its upper end, is rigidly secured to the co-operating sleeve-like head 29. The numeral 33 indicates a helical spring that surrounds the port-extending tube 32 and is 10 compressed between the receding piston head 30 and in an abutment afforded by a nut 34 that works adjustably with screw-threaded engagement in the exterior of the co-operating tube 32. The upper end of 15 each so-called port-extending tube 32 affords a port that will be brought into registration at proper times with admission ports 35 and exhaust ports 36 of the rotary controlling valve 20. In the arrangement shown, there 20 are three admission ports 35 located 120 degrees apart, and three exhaust ports 36, located 120 degrees apart, for each engine cylinder and, hence, for each tube 32. In this arrangement also, the adjacent admission and exhaust ports are located approximately 30 degrees apart. The admission ports 35 extend from the axial vapor chamber 20 of the rotary controller valve to the periphery of said valve and the exhaust port 30 36 open from the periphery of the valve into the annular exhaust chamber 21 of said valve.

The rotary controller valve is driven at proper speed from the master crank shaft 35 14, and with the arrangement of ports described, said valve should be given one-third of a complete rotation for each two rotations of said crank shaft. Otherwise stated, the rotary valve should make one 40 complete rotation for every six rotations of the engine crank shaft. This timing is, of course, for internal combustion engines of the four-cycle type. The connections for rotating the valve, as stated, are as follows:

The numeral 37 indicates a chain belt that runs over a sprocket wheel 38 on the engine crank shaft and over a sprocket wheel 39 journaled on a stud 40 secured to one end 50 of the housing 10. On its hub, the sprocket 39 carries a spur pinion 41 that meshes with a spur gear 42 on one end of the rotary controller valve. The sprocket 39 is twice the diameter of the sprocket 38 and the spur 55 gear 42 is three times the diameter of the pinion 41. This gives the timed action above stated.

The numeral 43 indicates a carburetor, which has a vapor delivery tube 44, the 60 upper delivery end of which is extended through one end of the controller valve and delivers into the axial vapor chamber 20 thereof. The numeral 45 indicates an exhaust pipe into which the annular chamber 65 21 of the controller valve discharges through

openings 46 in one end of the valve casing 16. In Fig. 2, the numeral 47 indicates a combined oil and water gauge that is connected to the interior of the crank chamber 11 by tubes 48 and 49. The numeral 50 70 indicates grease cups applied to the top of the valve casing 16 for supplying oil or grease to lubricate the rotary controller valve.

By reference particularly to Fig. 3, it will 75 be noted that the receding piston head 30 has a large sleeve 31^a that fits within the cylindrical piston 27 and, near its upper portion, has small vapor passages 51. The cylindrical piston 27, considerably above its 80 lower end, has vapor passages 52 and the cylinder 22, at the upper portion of its spiral conduit 23, has vapor passages 26. By reference to Fig. 2, it will be noted that the depending portion of the cylinder head 85 has an inclined oil passage 54, the lower portion of which is spoon-shaped and the upper extremity of which leads to the crank journal so that the crank journal will be 90 automatically lubricated.

Operation.

The operation of the engine, designed as described, is substantially as follows:

The crank shaft of the engine will be 95 rotated in the direction of the arrow marked on Fig. 2 and the rotary controller valve will be rotated in the opposite direction, that is also indicated by arrows marked adjacent thereto on Fig. 2. The several 100 engine units will perform their working, exhaust, intake and compression strokes in substantially the usual timing relation that is customary in four-cycle engines. In some instances, spark plugs might be provided, 105 but in the preferred form of the engine, high compression will be relied upon to produce ignition.

Figs. 6, 7, 8 and 9, particularly, illustrate 110 the valve action for controlling admission and exhaust throughout the one complete cycle of operation which takes place while the controller valve is being rotated through 120 degrees. In Fig. 6, it will be noted that the port-extending tube 32 is in communication with one exhaust port 36, so that the exhaust of gases is then from the cylinder that has just completed or about completed its working or power stroke. Fig. 7 shows the rotary valve moved about 115 30 degrees from the position shown in Fig. 6, which represents 180 degrees of movement of the engine crank shaft, thereby bringing one of the intake ports 35 into registration with the port tube 32 so that the explosive vapor from the carburetor will be drawn into that cylinder during the intake stroke. Figs. 8 and 9 show the positions of the controller valve during the 120 compression and power strokes.

When an explosion takes place in any one of the cylinders, the initial force of the explosion will, of course, be immediately effective to produce rotation of the engine crank shaft, but it will also be immediately effective to cause the piston head 30 to recede and compress the spring 33, thereby storing up power in said spring. The power thus stored up in the spring 33, at the instant of explosion, will produce the return movement of the piston head as the exploded gas is cool and thereby continue the application of power to the crank shaft. Thus, the force of the explosion is continued over a greater length of time or during a greater number of degrees of movement of the engine crank shaft than in the ordinary internal combustion engine and an action is obtained very much more like that obtained in a steam engine by expansion of caged steam.

In starting the engine, very volatile hydrocarbon fuel, such as high test gas, would advisably be used, but after the engine is once started, a much heavier hydrocarbon, such as kerosene, or even heavier hydrocarbon fuel, may be used.

During the time that a particular cylinder is making its suction stroke, the receding piston head 30 will be lowered or extended to its greatest distance into the cylinder and, at such time, the several vapor passages 51, 52 and 53 will be opened so that suction will then act through the spiral conduit 23 and intake port 24, and will open the check valve 25 while the lower end of said port 24 is passing through the oil y^1 and water y , and thus, a small amount of oil and a small amount of water in vapor form will be drawn into the cylinder during the suction stroke. It will, of course, be understood that the oil and water thus passed through the spiral conduit 23 and other passages noted, will, by the heat produced by the explosions, be converted into vapor. It is also important to note that the spiral conduit 23 is of increasing cross section from its receiving toward its delivery end, so that the oil vapor and steam will be permitted to expand as they pass through the conduit 23, thereby increasing the cooling effect on the engine. The steam and oil vapors thus delivered into the cylinder will be delivered at the upper end thereof while the explosive vapors drawn from the carburetor through the port tube 32 will be delivered into the lower end of the cylinder. This prevents direct commingling of the explosive vapors with the oil vapors and steam, but the latter, by heat from the explosions, will be superheated and further expanded so that they will prolong and continue the effect of the explosion. The oil vapors, of course, furnish good lubrication to the engine, cylinder and piston.

The adjustment of the spring 33 serves

to vary the compression under which the engines will act and variation of the compression will vary the time of firing. Obviously, the higher the compression, the earlier the explosion and, conversely, the lower the compression, the later the explosion.

It is further important to note that during the compression stroke and during the working stroke, the piston head 30 and its sleeve 31^a will be forced upward so that said sleeves will cut off communication between the ports 51 and 52, thereby preventing the escape of gases or vapors from the cylinder through said ports at such times.

What I claim is:

1. In an engine, the combination with a rotary valve, a crank and fixed supports for said valve and crank, of a cylinder journaled on the crank, and a tubular piston pivoted around the valve for oscillatory movement, said cylinder receiving an explosive charge through the piston from said valve and exhausting through said piston and valve.

2. The structure defined in claim 1 in which said piston has a spring-pressed receding head slidable thereon and co-operating with said cylinder.

3. In an engine, the combination with a rotary valve, a crank and fixed supports for said valve and crank, of a cylinder and piston one of which is journaled on the crank, and the other of which is pivoted around the valve for oscillatory movement and receiving an explosive charge and exhausting through said valve, and a spring-pressed receding piston head co-operating with said cylinder, said piston having an axial port-extending tube working through said receding piston head.

4. In an engine, the combination with a rotary valve, a crank and fixed supports for said valve and crank, of a cylinder journaled on the crank, a tubular piston pivoted around the valve for oscillatory movement, said cylinder receiving an explosive charge through the piston from said valve and exhausting through said piston and valve, and means for rotating said valve in respect to the crank shaft with action timed for four-cycle engine functions.

5. The combination with a crank shaft, a rotary valve and fixed supports for said shaft and valve, of a cylinder pivoted on said crank, a tubular piston working in said cylinder and having a sleeve pivotally mounted around said valve and equipped with a scoop port for delivering a fuel charge to said cylinder.

6. The combination with a crank shaft, a rotary valve and fixed supports for said shaft and valve, of a cylinder pivoted on said crank, a tubular piston working in said cylinder and having a sleeve pivotally mounted around said valve and equipped with a scoop port for delivering a fuel

charge to said cylinder, said port being in the form of a tube extended axially into said cylinder.

7. The combination with a crank shaft, a rotary valve and fixed supports for said shaft and valve, of a cylinder pivoted on said crank, a tubular piston working in said cylinder and having a sleeve pivotally mounted around said valve and equipped with a scoop port for delivering a fuel charge to said cylinder, said port being in the form of a tube extended axially into said cylinder, and a spring-pressed receding piston head working telescopically on said tube and within said cylinder.

8. The combination with a crank shaft, a rotary valve and fixed supports for said shaft and valve, of a cylinder pivoted on said crank, a tubular piston working in said cylinder and having a sleeve pivotally mounted around said valve and equipped with a scoop port for delivering a full charge to said cylinder, and a receding spring-pressed piston head working directly within that cylindrical portion of said tubular piston that is within said cylinder.

9. The combination with a crank shaft, a rotary valve and fixed supports for said shaft and valve, of a cylinder pivoted on said crank, a tubular piston working in said cylinder and having a sleeve pivotally mounted around said valve and equipped with a scoop port for delivering a fuel charge to said cylinder, and a receding spring-pressed piston head working directly within that cylindrical portion of said tubular piston that is within said cylinder, said piston head having an axial sleeve telescoped on said port-extending tube and within said cylinder.

10. The combination with a crank shaft, a rotary valve and fixed supports for said shaft and valve, of a cylinder pivoted on said crank, a tubular piston working in said cylinder and having a sleeve pivotally mounted around said valve and equipped with a scoop port for delivering a fuel charge to said cylinder, said cylinder having a surrounding conduit with a port at the outer end of said cylinder, and said cylinder and tubular piston having co-operating explosive charge passages for letting the explosive charge into the cylinder under the suction stroke, and a chamber containing liquid through which the port of said cylinder is arranged to sweep.

11. The structure defined in claim 1 in which said piston has a spring-pressed receding head slidable thereon and co-operating with said cylinder, and in further combination with means for varying the compression required to move said piston.

12. In an engine, the combination with a cylinder and co-operating piston having a receding head slidable thereon, of a spring acting on said piston head, and means for varying the tension of said spring whereby the compression produced by said piston head may be varied.

13. In an engine, the combination with a cylinder and co-operating piston having a receding head slidable thereon, of a spring acting on said piston head, means for varying the tension of said spring whereby the compression produced by said piston head may be varied, and means for reciprocating said cylinder in respect to the piston.

14. In an engine, the combination with a cylinder and co-operating piston having a receding head slidable thereon, means for reciprocating said cylinder in respect to the piston, of a spring acting on said piston head and holding the same for receding action under compression, and means for varying the tension of said spring to thereby vary the compression produced by the piston.

15. In an engine, a cylinder and a co-operating receding piston, said cylinder having a surrounding spiral oil and steam vapor conduit of increasing cross section, leading from the exterior of said cylinder to the interior thereof, and co-operating ports in said cylinder and piston arranged to open and close said vapor conduit with a properly timed action.

16. The combination with a crank shaft, a rotary valve and fixed supports for said shaft and valve, of a cylinder pivoted on said crank, a tubular piston working in said cylinder and having a sleeve pivotally mounted around said valve and equipped with a port for delivering to said cylinder, said cylinder having a surrounding oil and steam vapor passage of increasing cross section leading from the head end thereof and opening into said cylinder, and an oil container through which the intake end of said vapor passage is caused to sweep when the engine is in action.

In testimony whereof I affix my signature.
MICHAEL BECK.
